SAFETY RAZOR WITH RIBBON SHAPED BLADE

Nicolay Knudtzon Fougner, Lilleaker, near Oslo, Norway, assignor of one-half to Elvind Jensen Eckbo, Oslo, Norway

Application November 30, 1937, Serial No. 177,308
In Norway September 1, 1937

1 Claim. (Cl. 30—40)

The present invention relates to a safety razor with continuous ribbon shaped razor blade of the type specified in U. S. Patent No. 2,012,868 and which comprises a delivery and receiving 5 spool for the ribbon shaped blade located in a flat box, the ribbon shaped blade passing from one spool to the other over a clamping or guiding member, which is adapted to be displaced in a direction substantially perpendicular to a line 10 through the axis of the two spools, in order to clamp the ribbon shaped blade against a rib integral with the box.

The object of the present invention is to provide a safety razor of the kind specified, in which 15 the clamping or guard member and the means for pressing the same against the rib integral with the box may easily be removed from the box, so that boxes containing worn blades may quickly and easily be replaced with boxes containing unused blades without it being necessary 20 for the user to open the box and perform the removal and insertion of blades.

Preferably this is obtained in accordance with 25 the present invention by adapting the adjustable guard or clamping member, by means of which the ribbon shaped blade is pressed against the rib connected with the box, to be removed by means of an externally threaded hollow spindle, the connection between which and the adjustable 30 guard or clamping member is formed by means of a friction trunnion secured to the clamping member and fitting into the open end of the tubular spindle, so that the connection between the said spindle and the said adjustable guard 35 may be released by overcoming the friction resistance when the adjustable guard or clamping member has been removed a sufficient distance from the rib.

Preferably the friction trunnion may be rotatably connected with the guard or clamping member, although this is not absolutely necessary.

In order to prevent the guard plate from rotating about its central axis during its movement towards and away from the ribbon shaped blade the box is provided adjacent the rib with ribs or edges forming guides for the clamping or guard member in the longitudinal direction of the spindle.

50 The releasing of the guiding plate from the box in accordance with a further modification may also take place by providing the clamping or guard member with a short handle, adapted to engage with its free end an elastic pressure member on the box, by means of which the guard

is pressed against the ribbon shaped blade and the rib in such a manner that it may be removed in a lateral direction by pressing the elastic member downwards.

Some forms of the invention are illustrated on the drawings. Figure 1 is a view of the safety razor. Figure 2 is an axial section perpendicular on Figure 1. Figure 3 is a view of the safety razor with one half of the box removed. Figure 4 is a section on the line IV—IV on Figure 3. Figure 5 is a detail section of a modified embodiment and Figure 6 illustrates the latter embodiment with the guard plate swung sideways.

In accordance with the form illustrated on Figures 1-4, 1 is the box, the two disk shaped parts 2 and 3 of which contain the used and unused part of the ribbon shaped razor blade respectively. 4 is the rib connected with the box, against which the ribbon shaped blade is pressed by means of the guard plate 5, which is provided with teeth in the usual manner. The movement of the clamping plate or guard 5 in the direction against and away from rib 4 is caused by means of the externally threaded tubular spindle 6, which may be rotated by means of hand knob 7. The guard plate is provided with a friction trunnion 8, which may preferably be made in the same manner as an electric contact pin consisting of two elastic half cylinders, and which fits into the opening of the tubular 30 spindle 6.

This friction trunnion 8 may preferably be rotatably connected with the guard plate 5, although this is not absolutely necessary.

In the interior of tubular spindle 6 there is located a plunger 9, which is pressed outwards by means of a helical spring 10. Consequently the pressure of the guiding plate against the ribbon shaped blade and rib 4 cannot exceed the pressure determined by helical spring 10.

The receiving spool for the ribbon shaped razor blade is indicated at 11 and is rotated by means of two serrated disks 12, 13, which are screwed into the boss of the spool from opposite sides and with opposite direction of thread. 45 Preferably the threaded members of each disk 12, 13 may have different diameter in order to avoid confusion.

By turning the disks 12, 13 against the winding direction these may easily be removed from the box. The receiving reel is provided with an elastic pawl 14 adapted to engage depressions in one of the box walls so as to lock the reel against backwards turning.

55 In order to avoid dangerous stress on the razor

blade in case attempt should be made to turn the receiving reel when the blade is clamped between the guard member 5 and the rib 4 the receiving reel is provided with a braking device consisting of a pivoted or elastic lever, the inner 5 part of which cooperates with a shoulder on the receiving reel, whereas the free end has a depending tongue 17 in engagement with the knob 7 on spindle 6, so that the brake is put in action when the guard 5 approaches the clamping position and is only released when the razor blade is quite free between the guard and the rim.

In accordance with the form diagrammatically illustrated on Figures 5 and 6 the guard plate 5 is provided with a short arm 18, the end 19 of 15 which is in engagement with a head 20 pressed in the direction of rib 4 by means of spring 21. By depressing head 20 against the action of the spring to the position illustrated on Figure 6 the guard plate 5 may as indicated be swung out 20 laterally so as to be removed from the spool box.

I claim:

A safety razor comprising an oblong flat frame having a rib extending transversely across approximately the middle of one longitudinal side 25 thereof, a spool in one longitudinal end of the frame, a continuous ribbon shaped razor blade having one end secured to said spool, said spool being rotatable to wind used portions of said rib-

bon shaped blade thereon, the other end portion of said blade being coiled in the other longitudinal end of said frame, a clamping and guard member in said frame below said rib and between said longitudinal ends, said clamping and guard member being displaceable transversely of the major axis of the frame and adapted to clamp said blade into shaving position against said rib, means for moving said clamping and guard member comprising an externally threaded tubular spindle 16 provided with an open end, said spindle being connected to said clamping and guard member through the medium of a trunnion secured to said member and frictionally engaging in the open end of said tubular spindle, so that the connection 15 between the tubular spindle and the clamping and guard member may be released by overcoming the frictional resistance when the said member has been moved a sufficient distance from said rim, and a locking device for said spool, said locking device being connected to said tubular spindle and movable into locking engagement with said spool when the tubular spindle is actuated to move the clamping and guard member into engagement with the ribbon shaped razor blade and 20 out of locking engagement when said razor blade is disengaged.

NICOLAY KNUDTZON FOUGNER.
